CLAIM

The ornamental design for a combined pop handle and container, as shown and described.

DESCRIPTION

FIG. 1 is a front perspective view of a combined pop handle and container showing my new design.

FIG. 2 is a front perspective view thereof, the broken lines showing a heart are for illustrative purposes only and form no part of the claimed design.

FIG. 3 is a rear perspective view thereof.

FIG. 4 is a front view thereof.

FIG. 5 is a rear view thereof.

FIG. 6 is a left side view thereof.

FIG. 7 is a right side view thereof.

FIG. 8 is a top plan view thereof.

FIG. 9 is a bottom plan view thereof.

FIG. 10 is a front perspective view of an alternate embodiment of FIG. 1.

FIG. 11 is a rear perspective view of FIG. 10.

FIG. 12 is a front view of FIG. 10.

FIG. 13 is a rear view of FIG. 10.

FIG. 14 is a left side view of FIG. 10.

FIG. 15 is a right side view of FIG. 10.

FIG. 16 is a top plan view of FIG. 10; and,

FIG. 17 is a bottom plan view of FIG. 10.

The broken lines disclosing the environment related to the claimed design and the surface treatment are for illustrative purposes only, and form no part of the claimed design.

1 Claim, 17 Drawing Sheets
